UNITED STATES PATENT OFFICE

156,148

DESIGN FOR A SCARF OR THE LIKE

Herbert R. Nelson, New York, N. Y., assignor to Princess Fabrics Corporation, New York, N. Y.

Application February 2, 1948, Serial No. 144,211

Term of patent 3½ years

(Cl. D3—12)

To all whom it may concern:

Be it known that I, Herbert R. Nelson, a citizen of the United States, residing at New York city, in the county and State of New York, have invented a new, original, and ornamental Design for a Scarf or the like, of which the following is a specification, reference being had to the accompanying drawing, forming part thereof.

The figure is a plan view of a scarf or the like, showing my new design.

I claim:

The ornamental design for a scarf or the like, substantially as shown.

HERBERT R. NELSON.
